RADIO RECEIVER TUNING MECHANISM

Carel Jan van Loon, Eindhoven, Netherlands, assignor, by mesne assignments, to Radio Corporation of America, New York, N. Y., a corporation of Delaware

Application June 3, 1938, Serial No. 211,492
In Germany July 26, 1937

2 Claims. (Cl. 74—10)

The invention relates to a radio-receiving apparatus wherein a differential mechanism is connected between the spindle of the tuning condenser and the driving mechanism for this condenser. One of the members of this mechanism which are movable with respect to the driving shaft of the differential mechanism may co-operate in this case with a braking device whereas the other member of this mechanism which is 5 movable with respect to said shaft actuates the spindle of the tuning condenser.

The construction according to the invention is particularly advantageous if in such apparatus tuning is effected with the aid of a motor. In 15 this case the tuning condenser must be stopped at once after the correct tuning to some station or other has been effected. The velocities of rotation of the movable members of the differential mechanism may be altered or compensated in 20 this case in some way or other with the result that the transmission which is generally present between the shaft of the driving mechanism and the spindle of the tuning condenser is altered or suppressed respectively. For example, as has 25 been mentioned already, one of the members of the differential mechanism may co-operate with a braking device by which said member is held fast when the apparatus is not tuned to any station. Those parts of the mechanism which 30 transmit the motion of one shaft to the other, thus acquire the opportunity to push off against this stationary member and to actuate the other movable member. With the latter member is 35 coupled in this case, for example with the aid of a cable or of gear wheels, the spindle of the tuning condenser so that this condenser is turned as long as the one movable member of the differential mechanism is stationary. When one comes 40 within reach of some station or other, the braking device becomes inoperative. The bodies which transmit the motion of one shaft to the other, can no longer push off in this case on the originally stationary member, which is now, however, in motion, that is to say they can bring 45 about hardly any coupling. Due to the friction the tuning condenser remains stationary and the above-mentioned bodies, which remain in motion owing to the driving shaft, utilise the member coupled with the tuning condenser as a pushing-off member so that now the member co-operating 50 with the braking device starts rotating. If it is desired to leave the station once chosen, the braking device is actuated anew with the result that the initial state is restored. Thus it is consequently possible to stop the spindle of the tun-

ing condenser at once although the driving shaft may still remain in rotary motion.

In one favorable form of construction of the device according to the invention braking is effected with the aid of an electro-magnetic brake. 5 Relatively to ordinary (rotatory) magnetic couplings the advantage is obtained that the exciting coil may remain immovable so that a material simplification in the construction of the apparatus is obtained.

The differential mechanism may be formed in different ways; it may consist, for example, of a planet gear system. According to the invention, a simpler construction is obtained, however, if the shaft of the driving mechanism is surrounded 10 by a bush which is adapted to rotate with respect to said shaft and which acts as a race for balls which can run on the one hand in a path provided in said shaft and on the other hand in a path present in the member which co-operates 15 with the braking device. The said bush acts at the same time as the driving member of the spindle of the tuning condenser.

The invention will be explained more fully with reference to the accompanying drawing 20 25 wherein

Figs. 1 and 2 represent diagrammatically the above-described device.

A shaft which is journaled in bearings 1 and 2 is connected to the driving member. 10 de- 30 notes the spindle of the tuning condensers represented by the block 10'. A bush 4 is free to rotate on the shaft 3, said bush having apertures 5 into which fit balls 6. At one end said bush is provided with a pulley 7 on which runs a cord 35 or cable 8 which is also led over a pulley 9 which is rigidly mounted on the spindle 10. On the inside as well as on the outside the balls 6 protrude from the member 4 and, being clamped with a certain pressure, they run on the one hand 40 in a path 11 formed in the shaft 3 and on the other hand in a path 12 provided in a member 13. The latter member co-operates with an electro- 45 magnetic brake 14 which is formed by a core 15 surrounded by a plurality of wire-turns 16.

The device operates as follows:

When the driving shaft 3 rotates and when, upon operating the receiving apparatus, one is out of reach of some station or other the core 15 of the brake 14 is drawn against the brake disc 50 13 due to the magnetic effect of the electric current flowing through the wire turns 16, the disc 13 being consequently stationary. Rotation of the shaft 3 results in that the balls 6 which are clamped with a certain pressure, start rotating 55

and push off during this rotation against the stationary path 12 provided in the disc 13. Owing to the motion of the balls the bush 4 is carried along with them with the result that the pulley 7 sets in motion the cable 8 and therefore also the pulley 9 on the spindle of the tuning condenser. The apparatus is connected in such manner that within reach of some station or other the excitation of the coil 16 ceases so that the brake disc 13 can be set in motion. Now the balls 6 can no longer push off on the path 12 since the latter has become movable. Due to the friction in the drive mechanism of the tuning condenser the spindle 10 and therefore also the bush 4 remain stationary. This results in that the rotating balls 6 impart to the disc 13 a rotary motion the direction of which is opposite to that of the shaft 3. If it is desired to leave the station to which the apparatus is once tuned, the coil 16 must be excited anew owing to which the disc 13 is stopped again. Then the pulley 7 is caused to rotate again with the result that also the tuning condenser is carried along with it.

Although the construction represented may also be successfully utilised in those cases in which the shaft 3 is actuated by hand, it is particularly advantageous if, as has previously been observed, the shaft 3 has mounted on it a motor which serves to actuate the condenser so that when tuning is effected this motor may be allowed to run down without any disadvantage.

What I claim is:

1. In control apparatus for a radio receiver provided with tuning mechanism, a driving shaft adapted to control adjustment of the tuning

mechanism, gear means loosely mounted on said shaft and having an extension bushing which is provided with a ball cage, a race way formed in the driving shaft, a member having a second race way formed therein and adapted to cooperate with the balls in the ball cage, the loosely mounted gear means and its extension remaining stationary and said member assuming rotary motion so long as the driving shaft is in motion, means adapted to arrest the motion of said member whereby the loosely mounted gear means is mechanically coupled to the driving shaft, and additional gear means coupled to the first mentioned gear means for driving the tuning mechanism.

2. In control apparatus for a radio receiver provided with tuning mechanism, a driving shaft adapted to control adjustment of the tuning mechanism, a pulley loosely mounted on said shaft, a second pulley rigidly connected to the tuning mechanism, a cable entrained about said two pulleys, the loosely mounted pulley having an extension bushing which is provided with a ball cage, a race way in the driving shaft, a member having a second race way formed therein and encircling the balls in the ball cage, the loosely mounted pulley and its extension remaining stationary and said member assuming rotary motion so long as the driving shaft is in motion, and means adapted to arrest the motion of said member whereby the loosely mounted pulley is mechanically coupled to the driving shaft to thereby drive the tuning mechanism.
